ELECTRIC FLATIRON

Paul J. Kircher, Plainville, Conn., assignor to
 Landers, Frary & Clark, New Britain, Conn., a
 corporation of Connecticut

Application August 16, 1944, Serial No. 549,746

6 Claims. (Cl. 219—25)

1

This invention relates to thermostatically controlled electric flat irons and has particular reference to manually operable means for adjusting the thermostatically controlled switch so that the circuit will be made and broken at any desired temperature within a given range of operation.

The object of the invention is to provide an improved arrangement for adjusting the temperature control which is characterized by its simplicity in construction and the ease and facility with which it may be operated.

A further object of the invention is to provide an improved construction wherein the control knob or handle is maintained relatively cool, the arrangement being such that an undue amount of heat is not transmitted from the iron to the control knob.

A still further object of the invention is to provide an improved arrangement having a control or adjusting knob which may be very conveniently adjusted in a straight line extending longitudinally of the iron.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the accompanying drawing, wherein I have shown, for illustrative purposes, two embodiments which the present invention may take:

Figure 1 is a side elevational view of an iron with parts broken away and in which one embodiment of the present invention is incorporated;

Fig. 2 is a detail view, in cross section, the same being taken substantially on line 2—2 of Fig. 1;

Fig. 3 is a top plan view of the adjustable slide; 40

Fig. 4 is a view similar to Fig. 2 but showing another embodiment of the invention; and

Fig. 5 is a top plan view of the control knob shown in Fig. 4.

Referring to the drawing in detail, I have 45 illustrated a flat iron of a type which is now on the market. It is understood that this disclosure is by way of exemplification only and that the construction of the iron and the type of thermostatically controlled switch may be varied or changed without departing from the scope of the present invention. As here shown, the iron has a sole plate 10, a shell or cover 11, a sheet metal superdeck 12, and a handle 13. Mounted on the sole plate is a heating unit 14. 15 designates the 50

thermostat which may be in the form of a bimetallic bar secured to the sole plate and located in a recess therein. The switch which the thermostat controls may have a fixed contact 16 and 5 a movable contact 17, the latter being carried by a lever or switch arm 18. This lever is pivoted between its ends, as at 19, to a link 20 having an inverted U-shaped cross section. The forward end of the link is pivoted, as at 21, to a fixed portion of the iron. The forward end of the switch arm 18 has a depending tongue 22 which is located in the path of movement of the free end of the thermostatic bar 15 so as to be engaged thereby when the iron is heated up. The tongue 15 22 of the switch arm is adjusted with respect to the thermostat in accordance with the degree of temperature at which it is desired to operate the iron by a screw 23 which is threaded into an opening provided with a fixed plate 24. The 20 lower end of this screw has a projection which extends into an opening in the cross portion of the link 20. A spring 26 normally holds the link up against the lower end of the screw. The lower end of this spring is hooked to the switch 25 lever 18 and its upper end is hooked over an ear provided on the end of a bracket 27. This bracket is secured to the fixed plate 24 and has a portion lying within an opening 28 in the central portion of the top wall of the shell 11. The screw is 30 axially adjusted through an adjustable member or stem 30 which is mounted for turning movement in the bracket 27 in axial alignment with the screw. This member has a flat blade or shank 31 extending into a cross kerf in the upper end 35 of the screw. The stem is provided on its upper end with a cylindrical head 32, the periphery of which is serrated so as to provide a plurality of longitudinally extending splines or teeth. The numeral 33 designates a U-shaped yoke having a central opening provided with teeth adapted to mate with the splines on the head. Thus, the yoke may be adjusted on the head, this being of advantage in that preliminary adjustment of the control device may be made before assembling the handle on the iron.

Referring now to the improvements of the present invention and, particularly, to the embodiment shown in Figs. 1 to 3, the handle 13, which is preferably made of plastic material, has an integral bridge 40 disposed beneath the grip portion of the handle and extending from the front upright portion to the rear upright portion thereof. This bridge is slightly spaced above the top surface of the superdeck 12. It has on its under side a longitudinally extend-

ing groove or channel 41, the side walls of which form tracks for rollers or disks 42 journaled on a slide 43. The slide has an elongated body portion 44 extending lengthwise of the channel. The rollers are located above this body portion and are journaled thereon at opposite ends thereof by pins or studs 45. The slide has, projecting from opposite sides thereof, downwardly offset extensions 46 to which is secured an adjusting knob or handle 47 formed of plastic material or the like. The handle is of generally inverted U-shape and passes transversely over the bridge. The downturned ends of the knob are secured to the extensions by screws 48. The body portion of the slide has, at its corners, down-turned pointed projections or prongs 49 adapted to engage the top surface of the superdeck. The area of engagement between these projections and the superdeck is relatively small so that no appreciable degree of heat will be transmitted to the slide from the superdeck. The slide is further provided with a laterally extending downwardly offset arm 50 which extends through an elongated slot 51 located in and extending longitudinally of the top wall of the superdeck. Pivoted to this arm, as by means of a pin 52, is a bar 53 which forms a connecting member between the slide and the yoke 33. This bar slidably extends through aligned openings 54 in the upwardly extending arms of the 30 yoke.

It will be seen that, with the construction described, when the control knob is moved longitudinally of the bridge, the pivot 52 for the sliding arm 53 will move therewith with the result that the sliding arm will rotatably adjust the yoke 33. As the yoke is secured to the stem 30, and the stem is engaged with the screw 23, the latter will be axially adjusted thereby adjusting the relation between the lug 22 and the thermostatic bar 15. The control knob or handle 47 is very conveniently positioned for adjustment in a straight line longitudinally of the iron. Adjustment may be made from either side of the handle. It will be further noted that the control knob is maintained relatively cool, the arrangement being such that no appreciable amount of heat is transmitted from the body portion of the iron to the slide or the control knob.

Referring now to the embodiment shown in Figs. 4 and 5, the construction of the iron may be similar to that previously described. In this embodiment, the bridge 49' of the handle is somewhat T-shape in construction. It has a central medial web 60 extending along the top of the superdeck. The bridge has, at its side margins, depending flanges or ribs 61, the inner surfaces 62 of which are preferably downwardly and outwardly inclined. The slide 43' is slidably mounted along one side of the bridge. In the present instance, this slide is shown as comprising a piece of plastic material, the same having an integral knob 47' which has a pointer 63. The slide has a longitudinally extending groove 64 along its inner side which receives the side edge of the bridge. The slide has, at its opposite ends, wings or projections 65 which extend laterally beneath the rib 61 of the bridge. Each of these wings has an upstanding lug 66 provided with an inclined face 67 adapted to engage the inner surface 62 of the rib 61. Thus, the slide is hooked about one edge of the bridge. Directly pivoted to the slide intermediate its ends is a bar 53'. The bar is pivoted to the slide by

a screw 52'. The bar is offset, as at 68, so as to extend through the slot 51 in the superdeck 12. The bar 53', as in the preceding embodiment, extends through openings or slots 54 in the yoke 33. A leaf spring 70 is carried by the yoke and engages the under side of the superdeck for the purpose of holding the yoke down on the serrated head 32. The pointer 63 of the knob is adapted to cooperate with a temperature scale (not shown) provided on the top surface of the bridge for the purpose of indicating the setting of the slide. The operation of the device shown in Figs. 4 and 5 is generally similar to that of the arrangement shown in the preceding embodiment.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In an electric iron, a casing, a handle on the casing having a hand grip and a bridge beneath the hand grip extending longitudinally along and above the center line of the casing, thermal responsive means within the casing, a switch actuated by said thermal responsive means, means for adjusting said switch relative to said thermal responsive means and comprising a vertically disposed screw, manually operable means for setting said adjusting means and including a slide guided by and movable longitudinally of said bridge and an operative connection between said slide and screw comprising a horizontally disposed bar pivoted to said slide and associated with 40 said screw for radial movement relative thereto on sliding movement of said slide.

2. In an electric iron, a casing, a handle on the casing having a hand grip, thermal responsive means within the casing, a switch actuated by 50 said thermal responsive means, means for adjusting said switch relative to said thermal responsive means and comprising a screw and a yoke connected to the screw, a track located above and extending longitudinally of the casing 55 beneath the hand grip, and manually operable means for adjusting said screw and including a slide guided by said track, a knob carried by the slide and a bar pivoted to the slide and connected to the yoke for radial movement relative thereto.

3. In an electric iron, a casing, a handle on the casing having a hand grip and a bridge beneath the hand grip and extending longitudinally along and above the center line of the casing, thermal responsive means within the casing, a switch actuated by said thermal responsive means, means for adjusting said switch relative to said thermal responsive means and comprising a screw and a yoke connected to the screw, and manually operable means for adjusting said screw and including a slide movable longitudinally of said bridge, a knob on the slide, and a bar pivoted to the slide and connected to the yoke for radial movement relative thereto.

4. In an electric iron, a casing, a handle on the 75 casing having a hand grip, thermal responsive

means within the casing, a switch actuated by said thermal responsive means, means for adjusting said switch relative to said thermal responsive means and comprising a member mounted for angular adjustment about a vertical axis, a track located above and extending longitudinally of the casing beneath the hand grip and connected to said member and having a channel on its under side, a slide mounted in said channel for movement longitudinally thereof, a non-rotatable knob straddling said track and connected to said slide, and an operative connection between the slide and said adjusting means.

5. In an electric iron, a casing, a handle on the casing having a hand grip and a bridge beneath the hand grip extending longitudinally along and above the center line of the casing, said bridge having a channel on its under side, thermal responsive means within the casing, a switch actuated by said thermal responsive means, means including a member mounted for angular adjustment about a vertical axis for adjusting said switch relative to said thermal responsive means,

and manually operable means connected to said member for setting said adjusting means and including a slide guided by said channel and a non-rotatable knob straddling said bridge and connected to said slide.

6. In an electric iron, a casing, a handle on the casing having a hand grip and a bridge beneath the hand grip extending longitudinally along and above the center line of the casing, said bridge having a channel on its under side, thermal responsive means within the casing, a switch actuated by said thermal responsive means, rotary means for adjusting said switch relative to said thermal responsive means, and manually operable means for setting said adjusting means and including a slide beneath said bridge, rollers carried by said slide and engaging in said channel, a knob straddling said bridge and connected to said slide, and an operative connection between 15 said slide and adjusting means whereby the latter is turned upon longitudinal movement of said slide.

PAUL J. KIRCHER.
